Primary Examiner — Karen E Eldridge Powers

(57) CLAIM

I claim the ornamental design for a toothbrush with two heads, as shown and described.

DESCRIPTION

FIG. 1 is a front elevational view of the brush;
FIG. 2 is a rear elevational view of the brush;
FIG. 3 is a right side elevational view of the brush;
FIG. 4 is a left elevational view of the brush;
FIG. 5 is a rear and right side perspective view of the brush;
FIG. 6 is a rear and left side perspective view of the big head of the brush; and,
FIG. 7 is a right side and front perspective view of the small head of the brush.

1 Claim, 7 Drawing Sheets

FIG. 1

FIG. 2

FIG. 3

FIG. 4

FIG. 5

FIG. 6

FIG. 7
